DYEING OF ANIMAL FIBRES

John Robert Seemuller, Maisons-Laffitte, France, assignor to Societe Monsavon-l'Oreal, Paris, France, a corporation of France

No Drawing. Filed Dec. 10, 1956, Ser. No. 627,110

Claims priority, application France Dec. 10, 1955

3 Claims. (Cl. 167—88)

This invention relates to the dyeing of animal fibres, particularly live or dead hair and to dyeing compositions for use in the said process.

Various methods have been proposed for facilitating the dyeing of hair. For example, it has been proposed to add to the dye bath, or to a pre-treatment bath, emulsifying agents such as alkali salts of sulphonated fatty alcohols, condensation products of higher fatty acids with polyamines, and alkyl phenoxyethoxyethanols, the object being to increase the permeability of the hair to the dye. It has also been proposed to dissolve the dye in ethyl acetate or other similar solvent and to prepare an aqueous suspension from this solution with the aid of thickeners and/or wetting agents.

Generally speaking, these processes only afford a slight improvement in the dyeing and fixation of the dyes when considered in relation to the already appreciable affinity of the dyes for keratinic fibres at moderate temperature. Moreover, these methods considerably limit the range of dyestuffs which can be employed in hair dyeing. The present invention obviates these disadvantages and in addition makes it possible to dye live or dead hair by means of dyestuffs which have hitherto been regarded as substantially unusable for that purpose.

It is an object of the present invention to provide a dyeing process in which an increased range of dyes can be employed, more particularly for dyeing hair, which promotes and accelerates the development of the shade and fixing of the dye, and which may be effected at the ambient temperature or at a moderately low temperature (e.g. lower than 50° C.). It is a further object of the invention to provide a dyeing process for hair which enables dyeing to be carried out very satisfactorily, from the viewpoint of rapidity and intensity, by means of dyes normally having only very low affinity, or even no affinity, for hair under the aforesaid temperature conditions.

According to the present invention a composition for dyeing animal fibres comprises a solution of a direct dye in an aqueous organic solvent which is chemically indifferent with respect to the dye and to the product to be dyed, the said solvent being completely miscible with water in the proportion in which it is present and having the general formula:

in which R represents a monovalent aliphatic hydrocarbon group having a straight or branched chain containing 4 to 5 carbon atoms and n is 1.

In the foregoing group R, the branching may be either of the iso type (as for example in isoamyl alcohol).

Solvents of the aforesaid general formula include, for example, the products sold under the trademark "Carbitol," and also condensation products of lower aliphatic alcohols with ethylene oxide. Preferred solvents are 2-butoxyethanol ("Butyl Cellosolve"), and the product of condensation of isoamyl alcohol with ethylene oxide in the proportion of 1 mole of isoamyl alcohol to 1 to 4, and preferably 1.2 moles of ethylene oxide.

The above-defined organic solvent is preferably used in the proportion of 5-20% by weight of the dyeing solution. However, larger or smaller proportions of solvent may be present depending upon the desired effect and provided that the solvent is wholly miscible with water.

The inclusion of the solvent serves two purposes: on the one hand, it ensures, or increases the solubility of the dyestuff in the aqueous solution, and on the other hand, although the reason is not fully understood, the solvent appears to displace in favour of the fibre, the equilibrium which is established between the dyestuff, the water in which it is dissolved and the fibre.

The expression "direct dye" is used herein to mean a dyestuff capable of being directly applied to the fibre to give the final shade without involving the need of any chemical transformation such, for example, as oxidation, coupling or mordanting of the fibre.

The direct dyes thus defined are divided into the following classes in accordance with the various preferred embodiments of the invention:

(A) Nitro dyes, such for example as methyl-isoicramic acid and 1-hydroxy-2-amino-5-nitrobenzene;

(B) Azo dyes, such for example as those sold under the trade names:

25 Chrysoidine hydrochloride (No. 2 Color Index, 1st Edition, 1924)

Supracide" (Compagnie Française des Matières Colorantes)

Supramine" (Bayer)

"Kiton" (Ciba)

"Cibacet" (Ciba) and

"Solacet" (Imperial Chemical Industries Ltd.)

the last two to the extent to which they are actually azo dyes.

(C) Anthraquinone dyes, such for example as those sold under the trade names:

"Solway" (Imperial Chemical Industries Ltd.)

"Celliton" (B.A.S.F.)

"Acetoquinone S" (Compagnie Française des Matières Colorantes)

"Cibacet" (Ciba)

"Solacet" (Imperial Chemical Industries Ltd.)

"Cellit" (B.A.S.F.) and

"Fenacet" (General Dyestuff Corp. N.Y.)

to the extent to which the dyes known under the last four names are actually anthraquinone dyes.

(D) Pigment dyes insoluble in water, such as those sold under the commercial names:

"Orasol" (Ciba)

"Dispersol" (Imperial Chemical Industries Ltd.)

"Microsol" (Ciba)

"Duranol" (Imperial Chemical Industries Ltd.)

"Setacyl" (J. R. Geigy)

"Celliton" (B.A.S.F.)

"Acetamine" (E. I. du Pont de Nemours and Co.)

"Celanthrene" (E. I. du Pont de Nemours and Co.) and

"Artisil" (Sandoz) and also

"Cibacet" to the extent to which it is applied to insoluble pigment dyes.

(E) Basic dyes, such as Janus dyes (Bayer),

(F) Complex metalliferous dyes, e.g. those marketed under the trademarks:

"Irgalane" (J. R. Geigy A.G.)

"Lanasyne" (Sandoz S.A.)

"Carbolan" (Imperial Chemical Industries Ltd.)

"Cibalane" (Ciba)

(G) Dyes of the "Nigrosine" type

(H) Dyes of the "Induline" type

The compositions of the invention dye animal fibres, e.g. live hair, at ambient temperatures, i.e. ordinary room temperatures of 50-90° F.

The following examples will serve to illustrate the invention using dyes of the aforesaid types, having very low affinity, or even no affinity, for animal fibres such as hair under the normal conditions of application at ambient temperature. In all the examples, the percentages are by weight.

Except where otherwise stated, the specified solution is applied to the hair for 15 to 20 minutes at ambient temperature and the hair then rinsed with water.

EXAMPLES

(A) Examples of dyeing by means of nitro dyes

EXAMPLE I

The following solution is prepared:

	Percent
Methyl isopicramic acid	5
"Butyl Cellosolve" (2-butoxyethanol)	20
Triethanolamine	3
Water to make 100%.	

Applied to live hair, 50-60% of which is naturally white, a beautiful violet shade is obtained.

EXAMPLE II

The following solution is prepared:

	Percent
1-hydroxy-2-amino-5-nitrobenzene	0.5
"Butyl Cellosolve" (2-butoxyethanol)	20
Triethanolamine	3
Water to make 100%.	

By means of this solution a beautiful golden blonde shade is obtained on live, white hair.

(B) Examples of dyeing by means of azo dyes

EXAMPLE III

The following solution is prepared:

	Percent
Disperse Orange 8 (Colour Index, 2nd Edition, 1956, p. 1680)	3
"Butyl Cellosolve" (2-butoxyethanol)	10
Lactic acid	3
Water to make 100%.	

By means of this solution hair of a natural light brown shade is dyed a beautiful coppery shade comparable to that obtained with natural henna.

(C) Example of dyeing by means of anthraquinone dyes

EXAMPLE IV

The following solution is prepared:

	Percent
"Solway Blue RNS" (No. 1076, Colour Index, 1st Edition, 1924)	1
Condensate of isoamyl alcohol and ethylene oxide in molecular proportions of 1:1.2	10
Lactic acid	3
Water to make 100%.	

By means of this solution an intense blue shade is obtained on naturally white live hair.

EXAMPLE V.—DYEING BY MEANS OF CIBACET ANTHRAQUINONE DYES

The following solution is prepared:

	Percent
"Cibacet" dye is one of the types mentioned below	3
"Butyl Cellosolve" (2-butoxyethanol)	10
Lactic acid	3
Water to make 100%.	

Depending upon the dye employed, there is obtained on naturally white live hair by means of this solution a shade as follows:

Violet Cibacet 2R ----- Mauve.

Blue Cibacet F3R ----- Light blue.

Sapphire blue Cibacet 4G (is the colorant amino - oxy - anthraquinonique referred to as "Disperse blue 16"— Colour Index, 2nd Edition, 1956, p. 1720) ----- Turquoise blue.

EXAMPLE VI

The following solution is prepared:

	Percent
Alizarin Fast blue BE (referred "Acid Blue 129," Colour Index, 2nd Edition, 1956, p. 1287)	0.8
"Butyl Cellosolve" (2-butoxyethanol)	10
Lactic acid	3
Water to make 100%.	

By means of this solution an intense blue shade is obtained on naturally white live hair.

EXAMPLE VII

The following solution is prepared:

	Percent
Erio Fast Brown 5RL (referred "Acid Brown 11," Colour Index, 2nd Edition, 1956, p. 1333)	3
"Butyl Cellosolve" (2-butoxyethanol)	10
Lactic acid	3
Water to make 100%.	

A fairly viscous solution is obtained which dyes white hair dark chestnut.

EXAMPLE VIII

The following solution is prepared:

	Percent
"Orange Nyloquinone 2R" (referred "Disperse Orange III," Colour Index, 2nd Edition, 1956, p. 1676)	1
"Butyl Cellosolve" (2-butoxyethanol)	10
Lactic acid and water to make 100% at pH 7.	

By means of this solution a bright orange shade is obtained on naturally white live hair.

(D) Examples of dyeing by means of water-insoluble pigment dyes, known under the name "Orasol dyes"

EXAMPLE IX

The following solution is prepared:

	Percent
"Orasol" dye	1
"Butyl Cellosolve" (2-butoxyethanol)	10
Water to make 100%.	

Depending upon the dye employed, there is obtained on naturally white live hair by means of this solution a shade as follows:

"Orasol Blue BLW" (referred "Solvent Blue 10," Colour Index, 2nd Edition, 1956, p. 2876) Intense blue.
 "Orasol Blue 2GW" Blue-grey.

"Orasol Navy Blue RB" (referred "Solvent Blue 1," Colour Index, 2nd Edition, 1956, p. 2873) Slate blue.

(E) Example of dyeing by means of basic dyes

EXAMPLE X

	Percent
Janus Black R	2
"Butyl Cellosolve" (2-butoxyethanol)	10
Lactic acid to make pH 3.	
Water to make 100%.	

By means of this solution, a very intense grey having a mauve tinge is obtained on naturally white live hair.

EXAMPLE XI

The following solution is prepared:

	Percent
Janus yellow R (No. 236, Colour Index, 1st Edition, 1924)	1.1
"Butyl Cellosolve"	10
Water and ammonia to make 100% at pH 7.	

By means of this solution a bright golden blonde shade is obtained on naturally white live hair.

EXAMPLE XII

The following solution is prepared:

	Percent
Astracyanine B (referred "Basic Blue 18," Colour Index, 2nd Edition, 1956, p. 1644)	2
"Butyl Cellosolve" (2-butoxyethanol)	10
Water and ammonia to make 100% at pH 8.	

By means of this solution naturally white live hair is dyed a very deep blue shade and black hair is dyed a blue-black shade.

EXAMPLE XIII

The following solution is prepared:

	Percent
Chrysoidine hydrochloride (No. 20, Colour Index, 1st Edition, 1924)	0.1
"Butyl Cellosolve" (2-butoxyethanol)	10
Water to make 100%.	

By means of this solution a reddish-blonde shade is obtained on naturally white live hair.

EXAMPLE XIV

The following solution is prepared:

	Percent
Methyl violet (No. 680, Colour Index, 1st Edition, 1924)	0.05
"Butyl Cellosolve" (2-butoxyethanol)	5
Water to make 100%.	

By means of this solution a light mauve tinge is obtained on naturally white live hair.

(F) Examples of dyeing by means of complex metallic dyes

EXAMPLE XV

The following solution is prepared:

	Percent
Irgalane Dark Brown 5R—150% (referred "Acid Brown 48," Colour Index, 2nd Edition, 1916, p. 1348)	1.5
"Butyl Cellosolve" (2-butoxyethanol)	10
Lactic acid	4
Water to make 100%.	

15 By means of this solution a light brown shade is obtained on naturally white live hair.

EXAMPLE XVI

The following solution is prepared:

	Percent
Violet fonce Lanasyne (referred "Acid Violet 66," Colour Index, 2nd Edition, 1916, p. 1221)	2.5
"Butyl Cellosolve" (2-butoxyethanol)	10
Lactic acid	4
Water to make 100%.	

By means of this solution a very deep smoke-grey shade is obtained on naturally white live hair.

EXAMPLE XVII

30 The following solution is prepared:

	Percent
Cibalane Brown B.L. (referred "Acid Brown 19," Colour Index, 2nd Edition, 1956, p. 1336)	2.5
"Butyl Cellosolve" (2-butoxyethanol)	10
Lactic acid	3
Water to make 100%.	

By means of this solution a blonde shade is obtained on naturally white live hair.

40 (G) Example of dyeing by means of dyes of the "Nigrosine" type

EXAMPLE XVIII

The following solution is prepared:

	Percent
Nigrosine CBRS (No. 865, Colour Index, 1st Edition, 1924)	0.5
"Butyl Cellosolve" (2-butoxyethanol)	15
Lactic acid	2.5
Water to make 100%.	

By means of this solution, a beautiful grey shade having a mauve tinge is obtained on white hair.

(H) Example of dyeing by means of dyes of the "Induline" type

EXAMPLE XIX

The following solution is prepared:

	Percent
Induline R.A.L. (No. 861, Colour Index, 1st Edition, 1924)	1
"Butyl Cellosolve" (2-butoxyethanol)	10
Lactic acid	3
Water to make 100%.	

65 By means of this solution a beautiful grey-blue shade is obtained on white hair.

The invention is in no way limited to the use of a single solvent and it is possible without disadvantage, and sometimes even advantageously, to use two or more solvents of the foregoing general formula in combination, as in Example V.

The dyeing solutions may contain any of the usual adjuvants such as foaming agents, softeners and any other products intended to brighten or improve in any other manner the texture or appearance of the hair. It

is also possible to incorporate in such solutions a cream-base of usual type so as to produce a cream dye which is more readily applicable and which ensures a better distribution of the dye over the hair to be dyed, while preventing the contact of the dye with the scalp. The following is an example of such a cream dye:

EXAMPLE XX

The following solution is prepared:

	Percent
Nigrosine S (No. 865 in the color index, 1st edition)	3
Monobutylether of diethylene glycol or 2-[β -butoxy]-ethoxy-1-ethanol	10
Lactic acid	8
Water to make 100%.	

The solution is brought to about 50° C. on a water-bath, and the following incorporated:

	Percent
Lanette wax SX	15
Oxyethylenated alkylphenol	8

The cream thus obtained is allowed to cool.

This cream is applied at ambient temperature to naturally white live hair. It is left in contact therewith for 15 to 20 minutes, and the hair is then rinsed with tepid water. A beautiful clear grey shade is obtained.

I claim:

1. A method of dyeing live human hair which comprises applying thereto at room temperature a preformed dyestuff selected from the group consisting of acid dyes, basic dyes, dispersed dyes, direct dyes and solvent dyes in the form of a solution in a homogeneous aqueous mixture essentially consisting of water and 5% to 20% by weight of the dye solution of an organic water miscible solvent selected from the group consisting of 2-butoxy-

ethanol and a condensation product of 1 mole of isoamyl alcohol with 1.2 moles of ethylene oxide.

2. A method of dyeing live human hair which comprises applying thereto at room temperature a preformed dyestuff selected from the group consisting of acid dyes, basic dyes, dispersed dyes, direct dyes and solvent dyes in the form of a solution in a homogeneous aqueous mixture essentially consisting of water and 5% to 20% by weight of the dye solution of 2-butoxyethanol as an organic water miscible solvent.

3. A method of dyeing live human hair which comprises applying thereto at room temperature a preformed dyestuff selected from the group consisting of acid dyes, basic dyes, dispersed dyes, direct dyes and solvent dyes in the form of a solution in a homogeneous aqueous mixture essentially consisting of water and 5% to 20% by weight of the dye solution of a condensation product of 1 mole of isoamyl alcohol with 1.2 moles of ethylene oxide as an organic water miscible solvent.
